(57) **CLAIM**

The ornamental design for a water fountain, as shown and described.

DESCRIPTION

FIG. 1 is a top perspective view of the water fountain, showing the new design;

FIG. 2 is a front perspective view of the water fountain;

FIG. 3 is a front view of the water fountain;

FIG. 4 is a side view of the water fountain;

FIG. 5 is a rear view of the water fountain;

FIG. 6 is a top view of the water fountain; and,

FIG. 7 is a bottom view of the water fountain.

The broken line remainder of the water fountain showing the catch basin in the form of a well, the fountain producing device and the environment surrounding the water fountain are for illustrative purposes only and form no part of the claimed design.
